BOOT HEEL INSERT

William B. Hanko, 2710 Queen Ave., Cleveland, Ohio

Filed Dec. 9, 1963, Ser. No. 77,719

Term of patent 14 years

(Cl. D7—5)

FIG. 1

FIG. 3

FIG. 4

FIG. 2

FIG. 5

FIG. 6

FIG. 1 is a perspective view of the boot heel insert showing my new design;

FIG. 2 is a side elevation view of the boot heel insert;

FIG. 3 is a perspective view of the insert;

FIG. 4 is a bottom view of the insert;

FIG. 5 is a sectional view taken along line 5—5 of FIG. 2;

FIG. 6 is a perspective view of a modified form of the boot heel insert design shown in FIG. 1 wherein a pair of spaced apart narrow circumferential ribs have been applied to the outer cylindrical wall.

I claim:

The ornamental design for a boot heel insert, as shown and described.
